PORTABLE ELECTRIC HEAT GUN

Wilbert M. Gilman, Wellesley Hills, Mass., assignor to
Electronized Chemicals Corporation, a corporation of
Delaware

Filed Jan. 8, 1969, Ser. No. 15,249

Term of patent 14 years

Int. Cl. D8—02

U.S. Cl. D8—30

FIG. 1 is a perspective view of the portable electric heat gun, showing my new design.

FIG. 2 is a side elevational view of the unit.

FIGS. 3 and 4 are respective front and rear end views thereof.

I claim:

The ornamental design for a portable electric heat gun, substantially as shown.
